BAR OR SIMILAR ARTICLE

Gregory Muniz, 2280 E. 90th Ave.,
Thornton, Colo. 80229

Filed Oct. 24, 1965, Ser. No. 87,894

Term of patent 14 years

(Cl. D33—19)

FIGURES 3 and 4 are side views showing opposite sides of the bar of my invention; and

The back of the bar is plain and unornamented.

I claim:

The new, original and ornamental design for a bar or similar article, as shown and described.
